US0D1073931S

(12) **United States Design Patent** (10) Patent No.: **US D1,073,931 S**
(45) Date of Patent: ** May 6, 2025

(54) **CARTRIDGE BAG FUNNEL**

(71) Applicant: **Eitan Medical Ltd**, Netanya (IL)

(72) Inventor: **Elad Meidan**, Binyamina Givat-Ada (IL)

(73) Assignee: **Eitan Medical Ltd**, Netanya (IL)

(**) Term: **15 Years**

(21) Appl. No.: **35/517,704**

(22) Filed: **Mar. 16, 2023**

(80) **Hague Agreement Data**

Int. Filing Date: **Mar. 16, 2023**

Int. Reg. No.: **DM/229819**

Int. Reg. Date: **Mar. 16, 2023**

Int. Reg. Pub. Date: **Jul. 7, 2023**

(51) **LOC (15) Cl.** **24-02**

(52) **U.S. Cl.**

USPC **D24/128**
